UNITED STATES PATENT OFFICE.

FRANK ERBEN, OF CLEVELAND, OHIO.

DESIGN FOR A FOB.

40,392.

Specification for Design.

Patented Dec. 14, 1909.

Application filed September 13, 1909. Serial No. 517,537. Term of patent 3½ years.

To all whom it may concern:

Be it known that I, FRANK ERBEN, a citizen of the United States, residing at Cleveland, in the county of Cuyahoga and State of Ohio, have invented a new, original, and ornamental Design for Fobs, of which the following is a specification, reference being had to the accompanying drawing, forming a part thereof.

The figure is a plan view of a fob, showing my new design.

I claim:

The ornamental design for a fob, as shown.

FRANK ERBEN.

Witnesses:

MONROE E. MILLER,
JOHN A. BOMMHARDT.
